LEVELING BRIDGE

Werner H. Bothe, Kenosha, Wis., assignor to
 Worldsbest Industries, Inc., Cudahy, Wis., a
 corporation of Wisconsin

Application July 10, 1950, Serial No. 172,954

5 Claims. (Cl. 45—24)

1

The invention relates to stretching frames for use in drying curtains and other fabrics.

The usual frames for stretching curtains and other fabrics include frame members extending at an angle to each other and one of which frame members overlies the other angularly disposed frame member with the result that the impaling pins mounted on one of these frame members are raised above or out of the plane of the impaling pins on the other frame member. In situations of this kind a so-called levelling bridge or angularly disposed pin carrying plate is used to aid in clamping the fabric at the joint formed between the angularly disposed frame members. The object of the present invention is to provide a new and improved form of levelling bridge whereby the pins of the pin plate or bridge are aligned with and disposed between the pins of one of the angularly disposed members above referred to.

A further object of the invention is to provide a levelling bridge having a pin carrying plate which may be readily adjusted to assume different angular positions and which preferably may be clamped in its adjusted position by clamping means securing the levelling bridge to one of the stretcher frame members.

The invention further consists in the several features hereinafter set forth and more particularly defined by claims at the conclusion hereof.

In the drawings:

Fig. 1 is an elevation view of a stretching frame equipped with the levelling bridge embodying the invention;

Fig. 2 is a detailed vertical sectional view taken on the line 2—2 of Fig. 1;

Fig. 3 is a detailed horizontal sectional view taken on the line 3—3 of Fig. 1;

Fig. 4 is a perspective view of the leveling bridge and its mounting.

Referring to the drawings, I have shown a stretching frame including a top bar 5, end bars 6, a center bar 7, a bottom bar 8 lengthwise adjustably mounted relative to the end bars 6 and secured thereto by clamping devices 9, and a vertical adjustably mounted bar 10 adjustably secured to the top bar 5 by a clamping device 11 and to the bottom bar 8 by a clamping device 12 of known construction and by which the bar 10 is clamped against the back face of the bar 8.

The clamping devices 9 and 11 are shown as those of my prior U. S. Patent No. 2,448,574, dated September 7, 1948. The end bars 6 are

clamped in right angular relation with the top bar 5 by corner fittings 13, such as shown and described in my copending application Serial No. 76,401, filed February 14, 1949, for "Curtain Stretcher Corner Structure," now Patent No. 2,519,628 of August 22, 1950. The center bar 7 is shown as clamped to the top and bottom bars by fittings 14, more particularly shown and described in my copending application Serial No. 772,175, filed September 4, 1947, for "Curtain Stretcher," now Patent No. 2,572,979 of October 30, 1951.

From the above it will be noted that the stretching frame includes top and bottom bars, posts or end bars, and an adjusting bar clamped together by the various fittings mentioned above to form a frame, some of the bars being adjustable to accommodate curtains or fabrics of different widths and lengths.

10 The top bar 5, one of the end bars 6, the bottom bar 8, and the adjusting bar 10 are each provided with a row of pins 15 on which portions of the damp curtains or other fabrics are impaled to stretch the fabric and hold it in this condition until dried.

15 As previously noted, the present invention is directed to a levelling bridge used where two of the frame bars, such as the bars 8 and 10 are joined together in angularly disposed relation with the bottom bar 8 superposed over the adjusting bar 10 and in which instance the pins 15 on the bar 8 are in a plane above the pins of the bar 10. The bridge may also be used in other instances where the planes of the pins of 20 the bars are vertically displaced as at the joint between the top bar 5 and the bar 10 and the joint between the pinned end bar 6 and the bottom bar 8.

25 Referring to the drawings, the levelling bridge comprises a pin carrying plate 16 in the form of an angled plate having one side 17 adapted to extend parallel to one of the angularly disposed bars, here shown as the bar 10, and its other side formed to provide spaced ears or projections 18 in each of which the shank of a pin 19 is mounted, the disposition of the pins 19 being such that when the side 17 of the plate 16 is brought into abutting engagement with front edge of the bar 10, the pins 19 will be aligned with the row of pins 15 in the bar 10, and some of these pins 19 will be disposed between some of the pins 15 as shown in Figs. 1 to 3. This is a 30 desirable feature as it permits a more accurate pinning of the curtain, and both sets of pins 19

and 15 are functioning together for a portion of the length of the levelling bridge.

The levelling bridge or plate 16 may be secured in operative position in various ways by providing means for clamping it to one of the angularly disposed bars. The preferred construction shown in the drawings is to pivotally mount the bridge 16 by means of a pin 20 on the inner side of an angularly disposed side or leg 21 of a metal slide fitting or supporting bracket 22 whose opposite side 23 forms the web of a channel 24 within which the bar 10 is slidably mounted. For clamping the bracket 22 in lengthwise adjusted position on the bar 10 and also for simultaneously clamping the bridge 16 in the desired angularly adjusted position relative to the bars 8 and 10, a threaded screw 25 is anchored in the web 23 of the bracket 22 and extends through an aperture 26 in a U-shaped clamping head or jaw member 27 having angled feet 28 to engage the back edge of the bar 10, and a clamping nut 29, such as a wing nut, is mounted on the threaded end of the screw 25.

With the above construction, the bracket 22 with its attached bridge member 16 is slid over the lower end of the bar 10 before the said bar is clamped to the bar 8 by the clamping device 12. After the bottom bar 8 has been clamped to the bar 10 as shown in Fig. 1, the bracket 22 is moved along the bar 10 to the position shown in Fig. 1, and the bridge plate 16 is tipped on its pivot to the desired angle, as for example, that shown in Fig. 2, and then the nut 29 is screwed up on the screw 25 bringing the clamping member 27 against the back edge of the bar and drawing the body of the plate 16 against the front edge of the bar. In this position the pins 19 of the bridge plate 16 align with the pins 15 of the bar 10 and provide an inclined pinning path from the pins of the bar 10 to the pins of the bar 8 upon which the fabric may be impaled, thus eliminating the unpinned gap which occurs without a levelling bridge and improving the corner pinning anchorage for the curtain.

I desire it to be understood that this invention is not to be limited to any particular form or arrangement of parts except in so far as such limitations are included in the claims.

What I claim as my invention is:

1. In a stretching frame having angularly disposed and joined pin carrying frame members with one of said frame members overlying the other frame member, the combination of a support, means for clamping said support to one of said frame members, and a levelling bridge pivotally mounted on a horizontal axis on said support at one side thereof and provided with pins alining with the pinning of one of said frame

members and simultaneously active therewith and forming an inclined pinning path between the pinning of said members.

2. The structure as claimed in claim 1 wherein 5 the levelling bridge on said support is clamped against one of said frame members when said support is clamped in position.

3. In a stretching frame having angularly disposed and joined pin carrying frame members 10 with one of said frame members overlying the other frame member, the combination of a channelled bracket slidably mounted on one of said frame members and having an angled side adjacent the front edge of said frame member, 15 a pin carrying levelling bridge pivotally mounted on said angled side between said side and the front edge of said frame member, said bridge being disposable relative to said frame members to provide a pinning path between the pinning of 20 said members, and means for clamping said bracket to said frame member.

4. The structure as defined in claim 3 wherein the means for clamping the bracket to said frame member comprises a screw anchored to 25 said bracket, a clamping head engageable with the back edge of said frame member and through which said screw passes, and a clamping nut mounted on said screw and engageable with said clamping head.

5. In a stretching frame having angularly disposed and joined pin carrying frame members with one of said frame members overlying the other frame member, a levelling bridge mounted on one of said frame members and provided with 30 pins alining with the pinning of one of said frame members and forming an inclined pinning path between the pinning of said members, said bridge comprising an angled member, one of whose sides extends parallel to and abuts the front edge of 35 the frame member having the pinning alined with that on said bridge and the other side has spaced ears in which the pins are mounted, some of said ears lying between the pins on said frame member so that the pins on these ears are simultaneously active with the pins of the member having the alined pinning.

WERNER H. BOTHE.
